UNITED STATES PATENT OFFICE.

ANTONINO CHIBBARO, OF NEW YORK, N. Y.

MUSIC-ROLL PROTECTOR.

1,311,045.

Specification of Letters Patent. Patented July 22, 1919.

Application filed December 29, 1917. Serial No. 209,532.

To all whom it may concern:

Be it known that I, ANTONINO CHIBBARO, a citizen of the United States, residing at New York city, in the county of New York 5 and State of New York, have invented new and useful Improvements in Music-Roll Protectors, of which the following is a specification.

This invention relates to protecting devices 10 for music rolls adapted to be used upon piano players and like attachments and it consists in the novel features hereinafter described and claimed.

An object of the invention is to provide a 15 roll protector of simple and durable arrangement the parts of which may be easily and quickly manipulated in order to direct the sheet of music as it is being wound or unwound thereby preventing the sheet from 20 tearing or becoming damaged and also to provide a device which will properly present the sheet to the actuating mechanisms and thus improve the character of the music by presenting the sheet in an even and uniform 25 manner. The roll protector and the parts thereof may be made of any suitable material as for instance, metal, wood or rubber.

In the accompanying drawing:

Figure 1 is a front elevation of the music 30 roll protector.

Fig. 2 is a cross sectional view on line 2-2, Fig. 1 and Fig. 3 is a fragmentary view in perspective of the protector.

The music roll protector comprises a casing 35 1 in which suitable rollers 2 may be journaled for the purpose of supporting a perforated sheet 3, the said sheet being adapted to be passed or unwound from one roll 2 and wound upon the other and vice versa, in a 40 usual manner. The protector comprises a strip 4 which is secured to the rear wall and the ends of the casing 1. A bracket 5 is pivoted at its ends to the strip 4 and the said bracket is provided with ears 6 between 45 which a roll 7 is journaled. The bracket 5 is further provided with a flange 8 which extends over the upper portion of the roll 7. A lever 9 is fulcrumed at one end of the strip 4 and a link 10 is pivotally connected 50 at one end with one end of the lever 9 and pivotally connected at its other end with the end of the strip 4.

From the foregoing description taken in connection with the accompanying drawing, 55 it will be seen that when the lever 9 is swung

to an approximately vertical position the link 10 is moved longitudinally whereby the bracket 5 is swung and the roll 7 is moved above and out of contact with the sheet 3. When the lever 9 is swung to an approximately horizontal position the link 10 is moved down under the end of the bracket 5 and the said bracket is swung whereby the roll 7 is brought toward the front of the casing 1 and is permitted to rest upon the upper 60 surface of the sheet 3. Consequently as the sheet passes from one of the rollers 2 to the other roller 2 the said roll 7 maintains the sheet in a flat condition and prevents the same from becoming ruffled or tearing and 65 thus preventing injury to the sheet when the same is being moved from one roller to the other.

From the foregoing description taken in conjunction with the accompanying drawing, 70 it will be seen that a protector of simple and durable form is provided and that the same may be easily and quickly manipulated to engage a sheet or to release the same in order that the sheet may be removed from 75 the casing. When the roll of the attachment is in engagement with the sheet it maintains the sheet in a proper condition and protects the sheet against wear and damage.

Having described the invention what is 80 claimed is:—

1. The combination with a frame, music rolls journaled therein and adapted to support a perforated note sheet, of a protector comprising a bracket secured to the rear of 90 said casing, arms projecting forwardly from said bracket, a swingingly mounted plate, a roller journaled in said plate and bearing against the note sheet wound about the adjacent music roll; ears extending from the 95 plate between said arms and pivotally connected thereto, a link pivoted to one of said ears, and a lever fulcrumed on said arm and having one end pivotally connected to the adjacent extremity of said link, whereby said 100 plate and roller may be moved out of engagement with the perforated note sheet.

2. The combination with a frame, music rolls journaled therein and adapted to support a perforated note sheet, of a U-shaped 105 bracket secured to the rear wall of the casing and having its parallel limbs projecting forwardly, a normally disposed horizontal plate pivotally mounted upon said limbs, a roller arranged beneath the plate and carried 110

thereby, said roller normally bearing against the note sheet wound about the adjacent music roll; a lip formed on the plate and arranged in advance of said roller, a lever 5 fulcrumed on one of said limbs, and a link operatively connecting the lever with said plate, whereby the latter together with said roller may be moved toward and away from the adjacent music roll.

10 3. The combination with a frame, music rolls journaled therein and adapted to support the perforated note sheet, of a bracket secured to the rear wall of the casing, and including forwardly projecting arms, a nor-

mally disposed horizontal plate, spaced pairs 15 of parallel ears depending from said plate, one pair of ears being pivotally mounted upon said arms of the bracket, a roller arranged between the other pair of ears, and normally bearing against the note sheet 20 wound about the adjacent music roll; a lever fulcrumed upon one of said arms, and a link operatively connecting the lever with said plate, whereby said plate may be elevated to move the roller out of engagement with said sheet.

In testimony whereof I affix my signature.
ANTONINO CHIBBARO.
